Inventor:

Lewis Wolff
By James L. Norris, Atty.

UNITED STATES PATENT OFFICE.

LEWIS WOLFF, OF LONDON, ENGLAND.

ERASER.

SPECIFICATION forming part of Letters Patent No. 286,889, dated October 16, 1883.

Application filed February 28, 1883. (No model.) Patented in England November 20, 1882, No. 5,515.

To all whom it may concern:

Be it known that I, LEWIS WOLFF, of London, England, have invented new and useful Improvements in Devices for Erasing Pencil, 5 Ink, or other Marks, (for which I have obtained a patent in Great Britain, No. 5,515, bearing date November 20, 1882,) of which the following is a specification, reference being had to the accompanying drawings.

10 My invention relates to devices for erasing pencil, ink, and other marks from paper or other material, and comprises a case or holder so constructed that when not in use the erasing material can be folded within the same, 15 and be thereby kept clean when carried in the pocket.

The particular construction of my pocket-eraser will be fully hereinafter described in detail, and the improvements pointed out in 20 the claims.

In the accompanying drawings, Figure 1 is a side view of an erasing device constructed according to this invention, and showing one piece of the erasing material open and ready 25 for use. Fig. 2 is an edge view of the same. Fig. 3 is a side view, illustrating a modification of my invention. Fig. 4 is an edge view of the same.

According to the said invention, the case or 30 holder consists of two thin flat pieces of wood or other suitable material, *a a*, preferably of oblong form, although other forms may be used. Between these side pieces, *a a*, I place at one end a tablet of india-rubber, *b*, and at 35 the other end a tablet of ink-eraser, *c*, (which is india-rubber incorporated with glass powder or other suitable cutting material;) or both ends may be provided with the same material. In each end of the case, passing through the 40 two sides thereof and the erasing material, I fix a rivet or screw, *d*, thereby securing the erasing material between the two sides of the holder, but leaving each tablet free to turn upon its pivot. The holder is also provided 45 with notches *e e* on its edges, to enable a person easily to take hold of the erasing material and withdraw it from the said holder. The two pieces *b c* of erasing material which are held by the pivots are cut flush with the ends of the 50 case, to give the device a neat appearance. The

free ends are inclined, as shown in Fig. 1, so that when not in use they can be folded between the two sides of the holder without waste of room, (which would be the case if the ends were square,) and be thereby protected from 55 dirt; also the pointed form thus given to the erasing material facilitates its use. I sometimes arrange pins or other suitable stops, *f*, in the holder in order to support the erasing material and prevent it from turning round 60 when open and in use.

In a modification of this invention shown in Figs. 3 and 4, the holder is adapted to hold one kind of erasing material *g* only, pivoted at *d*, in which case the two sides *a a* of the 65 said holder, at the end which has no erasing material, are separated or kept apart by a piece of wood or other suitable packing, *h*, firmly secured between them by means of rivets *i i*, or the like; or the holder may consist of 70 one piece of wood of suitable size having a longitudinal recess formed in it to receive the eraser, in which case the packing *h* may be dispensed with.

Heretofore a rubber eraser has been composed of two semicircular shells, one containing a circular disk of rubber and the two united by a pivot. In another instance an eraser has been composed of an erasing tablet arranged in a flat tubular case having a central longitudinal slot in one side, through which projects a pin attached to the tablet, whereby the latter can be slid within the case to project or retract the end or ends of the same; and, further, a ferrule has been secured to the end of a pencil 75 and provided with two arms between which is centrally pivoted a tube carrying in one end 80 a pencil-eraser and in the other end an ink-eraser, so that the head can be rotated and held by a sliding sleeve for the purpose of using either eraser. My invention differs from 85 such constructions, as will be obvious from the foregoing specification.

What I claim is—

1. As an improved article of manufacture, 95 an eraser composed of two flat plates, *a a*, secured together with a space between them, and an erasing tablet having one end pivoted between the two plates at one end thereof by a transverse pin passing through one end of 100

the plates and the tablet, the other ends of the plates being connected by a transverse pin, substantially as described, whereby the tablet can swing horizontally from between the plates 5 to project longitudinally therefrom in the direction of their length, as set forth.

2. An eraser composed, substantially, of two flat parallel plates, *a a*, having side notches, *e e*, and secured together with a space between them, and an erasive tablet having one end pivoted between the two plates at one end thereof by a transverse pin, substantially as and for the purpose described.

3. An eraser composed of two flat plates

and two erasive tablets secured, respectively, 15 between the plates at the ends thereof by independent pivot-pins which pass through the tablets and serve to connect the plates, substantially as described, whereby either tablet can be swung from between the plates or 20 turned back therein, as set forth.

In testimony whereof I have hereunto signed my name in the presence of two subscribing witnesses.

LEWIS WOLFF.
